UNITED STATES PATENT OFFICE.

JAMES C. HOLLOWAY, OF SAN FRANCISCO, CALIFORNIA.

OATMEAL-MACHINE.

SPECIFICATION forming part of Letters Patent No. 324,556, dated August 18, 1885.

Application filed May 11, 1885. (No model.)

To all whom it may concern:

Be it known that I, JAMES C. HOLLOWAY, of the city and county of San Francisco, and State of California, have invented an Improvement in Oatmeal-Machines; and I hereby declare the following to be a full, clear, and exact description thereof.

My invention relates to that class of oatmeal-mills in which a rotating perforated rim is adapted to cut the oats against an exterior annular series of knives; and my invention consists in the devices hereinafter described and claimed.

The object of my invention is to provide a simple, effective, and rapidly-working oatmeal-mill of great capacity.

Referring to the accompanying drawings, Figure 1 is a perspective view of my mill, several parts being broken away to show interior portions. Fig. 2 is a vertical section of same on a smaller scale.

A is the frame or stand of the mill, on top of which is a plate, B, having an upwardly-extending flange, b, to which the annular series of knives C are secured. The knives have cutting-edges on each side, which are separated sufficiently to permit the egress of the cut oats or grain.

D is a vertical shaft suitably stepped in the base of the stand, and journaled in the top plate, B. It carries on its top a head, E, on the periphery of which is formed or secured the perforated rim or flange F, which lies just within and is concentric with the annular series of knives. The head E also carries radial arms or wings e, which extend from its central upwardly-projecting hub, e', and stop short of the perforated rim.

G is a cap-plate, on the under surface of which is secured an annular flange, H, the outer surface of which is provided with a series of parallel-spaced ribs, h, which, though they may be straight, are preferably arranged in an inclined or angling position, in order to produce a better feeding effect. The cap fits and rests upon an exterior shell or curb, I, which encircles the knives, though separated therefrom, leaving an annular discharge-chamber, i, and rests upon a rabbet formed on the top plate, B. When the cap-plate is in position, the flange H lies within the perforated

rim and just beyond the ends of the wings e, and the depth of the flange is such that its lower edge does not touch the surface of the head E, but lies just above it, leaving a small feed-space for the oats to pass from within under the flange and into the space between the flange and perforated rim, which space is occupied by the inclined or angling ribs, Fig. 2. The center of the cap-plate is provided with an aperture, g, which communicates with the feed space or chamber e', inclosed by the flange H, of which space the head E forms the floor. Into this aperture is let a feed-hopper, J, the neck of which lies just above the hub e' of the head. By pushing the hopper down so that its neck rests upon the hub, the feed may be entirely cut off; and by raising it to different points the amount of feed may be regulated and controlled. The upper edge of the perforated rim rises just above the knives, and is provided with stirrers or wipers K, which consist of small bars extending downwardly into the space inclosed by the outer shell or curb, and provided with feet k, which travel just above the top plate, B.

L is the discharge-chute communicating with the discharge-chamber.

M is a pulley on shaft D, by which it is driven.

The operation of the mill is as follows: Suitable power is applied to shaft D to rotate it, whereby the head E and its perforated rim F are rotated. The knives C are stationary, as are the ribs h. The oats are fed into hopper J, and thence pass through the center of the cap-plate G into the feed-chamber e'. Here, under the influence of centrifugal force, assisted by the positive action of the wings e, and also by the outward blast from within, caused by the rapidly-rotating wings, the oats pass under the stationary flange H into the space between said flange and the perforated rim. In this space they encounter the stationary angling or inclined ribs, against which, on account of their inclination, the oats rise up, spreading themselves out and presenting themselves to the perforated rim over its entire surface. This is of great advantage in causing an equal wear upon the perforated rim, but more especially in bringing all of its surface into action. The oats, projecting

through the perforations of the rotating rim, are cut against the knives, the cut sections dropping out between said knives into the discharge-chamber. Here they are met by the 5 wipers, and are forced into the discharge-chute. It will be noticed that in this mill the feed and passage of the oats are continuous, and distributed throughout the entire circle. This increases the capacity of the machine 10 materially, and avoids any clogging. The feed is, moreover, rapid, each oat finding its passage in the most direct manner.

The parts are so constructed and put together that any portion of the mill may be 15 easily reached; but this is especially true of the knives, which can be adjusted readily by removing the outer shell and watching where they may need alteration while the head E is rotating.

20 I am aware that an annular rotating perforated rim, concentric with an annular series of fixed knives, is not new, and I do not claim such, broadly; but—

What I do claim as new, and desire to secure by Letters Patent, is—

1. In an oatmeal-machine, a fixed annular series of knives and a rotating head having an upwardly-extending perforated annular flange lying within the circumference of the knives, 30 in combination with a fixed annular flange having on its outer surface a series of parallel inclined or angling ribs, said flange being within the circumference of the perforated rim and having its lower edge raised above the 35 surface of the head, whereby a passage is left for the oats, substantially as herein described.

2. In an oatmeal-mill, a rotating head provided with an annular perforated rim and a fixed annular series of knives exterior to the 40 rim, in combination with an annular flange provided with parallel-spaced ribs on its outer surface, said flange and ribs lying within the circumference of the perforated rim and having its lower edge raised above the head, to 45 provide a passage for the oats, and means for feeding the oats into the space inclosed by the flange, substantially as herein described.

3. In an oatmeal-mill, the combination of a

fixed annular series of knives, a rotating head provided with an annular perforated rim 50 within the circumference of the series of knives and radial wings on the head, and an annular flange having a series of inclined or angling ribs on its outer surface, said flange lying within the circumference of the perforated rim and beyond the ends of the wings 55 and having its lower edge raised above the head, substantially as and for the purpose herein described.

4. In an oatmeal-mill, the combination of 60 the top plate, B, having the series of knives C, the rotating head E, having a perforated rim, F, lying within the knives, the outer shell or curb, I, resting on the top plate and forming a discharge-chamber between itself and 65 the knives, the centrally-perforated cap-plate G, resting on the outer shell, and the downwardly-extending flange H on the cap-plate, having a series of inclined or angling ribs, h, 70 on its outer surface, said flange lying within the circumference of the perforated rim and having its lower edge raised above the head, substantially as herein described.

5. An oatmeal-mill, comprising the top plate, B, having the fixed annular series of 75 knives C, the outer shell or curb, I, encircling the knives and forming a discharge-chamber, i, a discharge-chute, L, the rotating head E, having an annular perforated rim, F, within the circumference of the series of knives, the centrally-perforated cap-plate G, resting on the outer shell and having an annular flange, H, 80 provided with angling-ribs h on its outer surface, said flange lying within the circumference of the perforated rim and having its lower edge raised above the head, and the hopper J, fitted in the center of the cap-plate, all arranged and adapted to operate, substantially as herein described.

In witness whereof I have hereunto set my 90 hand.

JAMES C. HOLLOWAY.
